UNITED STATES PATENT OFFICE.

WILLIAM T. SHERER, OF CHICAGO, ILLINOIS.

DESIGN FOR A DISPLAY-COUNTER.

55,490.

Specification for Design. Patented June 15, 1920.

Application filed February 11, 1920. Serial No. 357,822. Term of patent 14 years.

To all whom it may concern:

Be it known that I, WILLIAM T. SHERER, a citizen of the United States, residing at Chicago, in the county of Cook and State of Illinois, have invented a new, original, and ornamental Design for Display-Counters, of which the following is a specification, reference being had to the accompanying drawing, forming part thereof, which shows a perspective view.

I claim:

The ornamental design for a display counter as shown.

WILLIAM T. SHERER.
